SASH-LOCK.

1,072,099.

Specification of Letters Patent.

Patented Sept. 2, 1913.

Application filed February 10, 1912. Serial No. 676,916.

To all whom it may concern:

Be it known that I, LEWIS ELMER DE NEERGAARD, a citizen of the United States, residing in the city of Port Chester, county 5 of Westchester, and State of New York, have invented certain new and useful Improvements in Sash-Locks, of which the following is a full, clear, and exact description, reference being had to the accompanying 10 drawings, forming part of this specification.

This invention relates to improvements in sash locks, and particularly to that class of sash locks comprising two members slidably 15 connected to each other adapted to clamp the device between the outer sash and the frame molding of a window so as to secure the sashes in position; and its main object is to provide a sash lock of the kind mentioned 20 having means for fastening the same to the inner sash of a window in order to prevent its removal.

A further object of this invention is to provide a sash lock of an improved and 25 novel construction, attractive in design, and having simple and inexpensive operating means capable of effectually locking the device in position.

A still further object is to provide an improved sash lock comprising two oppositely moving members slidably connected to each other, capable of clamping the device between the frame molding and the outer sash of a window, having means for attaching 35 the same to the inner sash in such a manner as to allow a free operation of the two moving parts.

Another object of this invention is to provide a sash lock comprising two oppositely 40 moving members adapted to clamp the device between the frame molding and the outer sash of a window, having serrations in two opposite senses effectively locking the sash against movement in both directions.

A still additional object of this invention is to provide in a sash lock of the kind mentioned, simple and inexpensive means for adjusting the device to any size window.

With these and other objects in view such 50 as will more fully appear as the description proceeds, this invention consists in certain constructions and arrangements of parts such as will be hereinafter fully described 55 and claimed in the appended claims.

Sash locks having means for clamping the outer sash of a window against the frame molding have been heretofore made, the main object of these devices being to insure a window from being opened from the outside; for this reason they are generally called safety locks. One inconvenience that I have however noted in some of said devices, is that no means are provided for securing the same to any part of the window. 60 Another inconvenience which I have noticed in sash locks is that the same are generally operated by a separate key which may be easily lost or misplaced. Moreover, I have noted that such devices are usually 70 provided with serrations in one sense only which do effectually prevent the motion of the sash in one direction, but which do not give the same safety against movement of the sash in an opposite direction. A device 75 of this kind must necessarily be strong or in other words exert strong clamping action against the sash, especially when the same is used for safety purposes; and in the devices which have come to my knowledge, 80 such clamping action is exerted by means of an adjusting screw mounted on one of the members and controlling the other member. While the clamping action due to the screw is usually very effective, the appearance 85 of the device is rather unsightly and the cost of the same is necessarily higher than that of corresponding devices, in which sheet metal parts produced by means of dies are employed. 90

My improved device may be made entirely of sheet metal and in the drawings I have shown several forms in which the same may be made.

Referring to said drawings, Figure 1 is a 95 front view in elevation of my improved device made adjustable to any size window; Fig. 2 is a side sectional view in elevation of the same; Fig. 3 is a plan sectional view of the same; Fig. 4 is a detail side view 100 in elevation of the clamping surface adapted to rest against the outer sash of a window; Fig. 5 is a side view in elevation showing the serrated flange adapted to rest against the frame molding; Fig. 6 is a front view 105 in elevation of the bearing member used in the device shown in Fig. 1; Fig. 7 is a front view in elevation on a smaller scale of the adjustable member used in the same; Fig. 8 is a front view in elevation of a cap shaped 110

member having outwardly directed flanges attached to the operating member of the device shown in Fig. 1; Fig. 9 is a plan view of the same; Fig. 10 is a front view in elevation of the locking member used in the device shown in Fig. 1; Fig. 11 is a side view in elevation of the same; Fig. 12 is a plan view of the same; Fig. 13 is a front view in elevation of a simplified form which may be assumed by my device; Fig. 14 is a side sectional view in elevation of the same; Fig. 15 is a front view in elevation of a device having different clamping means rendered adapted to be attached to the inner sash of a window, according to one of the details of my invention; Fig. 16 is a plan sectional view of the same; Fig. 17 is a plan view of a key or wrench which may be used in connection with the operating member shown in full lines in Fig. 1; Fig. 18 is a side view of the same; Fig. 19 is a front view in elevation of a device similar to that illustrated in Fig. 13, fitted with only one serrated flange resting against the outer sash of a window; and Fig. 20 is a plan sectional view of the same.

My device is essentially composed of a bearing member 21 to which is slidably connected an adjustable member 22, controlled by an operating member 23 mounted on said bearing member 21. Part 22 may be slidably connected to part 21 in any convenient manner, and the drawings show a preferred form of construction in which part 22 is retained by part 21 by means of an upper flange 24 and lower flanges 25, 26 bent over the same.

Bearing member 21 is provided with a flange 27 adapted to rest against the frame molding of a window, and adjustable member 22 is provided with a narrower flange 28 adapted to rest against the outer sash. Said flanges are provided with serrations 29, 30, in opposite senses, adapted to lock the device in opposite directions and to prevent the moving of the sash both up and down. One of the said slidable members and preferably the inner member or bearing member 21, is provided with a right angle lug or projection 31, having a longitudinal elongated slot 32; said slot is used for the passage of a screw 33 retaining the device attached to the inner sash of a window. The drawings show lug or projection 31 at the lower part of the device, the same being intended for the usual style of window in which the inner sash normally occupies the lower section of the same; by means of lug or projection 31, the device can therefore be attached to the top rail of said inner sash, as illustrated in Fig. 1.

The opening for the passage of the screw is preferably made elongated as shown, to allow the device to be slightly moved by hand when released from its clamping posi-

tion, so as to detach both flanges from the respective surfaces formerly clamped and to permit the free motion of the window sashes. Screw 33 can be provided with a shoulder 34 allowing the same to go only to a certain depth, and preventing the head of the same 35 from clamping projection 31; the distance between shoulder 34 and the lower face of head 35 will be a trifle more than the thickness of said lug or projection 31, allowing the same to be moved by hand, but at the same time retaining the same in position.

To effect the locking of the devices, I provide a cam-slotted member 23 having a slot 36, and pivoted at 37 to bearing member 21. Adjustable member 22 is provided with a projecting pin 38 passing through said slot; and it can be easily seen that by turning member 23 around pivot 37, slot 36 acting on pin 38 will cause adjustable member 22 to move in or out in relation to bearing member 21.

In Fig. 1, the device is shown in its extended position; by turning member 23 to the left, member 22 will be moved inward and the clamping action of the device released. By properly shaping slot 36 the grip of this lock can be caused to be most powerful, and quite sufficient for all the requirements of such a device. Member 23 can be operated by means of an attached handle, as shown in dotted lines in Fig. 1 and designated by numeral 39, or else may be operated by a detached handle of any suitable description. Such a construction is also shown in full lines in Fig. 1 in which member 23 is formed in the shape of a disk provided with notches 40, into which can be inserted prongs 41 of an operating key 42 represented in Figs. 17, 18. As hereinbefore stated, it is most important that a device of this kind be fitted with retaining means to prevent its easy removal. While the slotted lug or projection 31 described serves its purpose quite well, and while the device can lock the window sashes in any position, the relative motion which may take place between the lower sash and the device due to the elongated form of slot 32, does not efficiently prevent the lower sash from rattling when the wind is blowing. I have found that in such a device it is very desirable that means be also provided for preventing the rattling of the window, this constituting an additional advantage and removing the cause of much annoyance.

In Fig. 5, I show a way of attaching the device, also preventing the rattling of the lower sash due to the wind when the device is in its clamping position. To this end the device is attached to the lower sash by means of a screw 43 having a threaded projecting portion 44 and a locking nut 45. Said nut 45 can be operated by hand and by tighten-

ing the same when the device has been clamped in position, the lower sash will also be effectively locked to said device and any motion of the same prevented. In a sash lock of moderate dimensions, such as would be adapted for this kind of an article, the adjustment due to a slot of the shape shown in the figures cannot be very high if the lock is expected to exert a strong clamping action; and therefore when it is desired to have a device which shall be adaptable for every size window, it will be necessary to provide an extension adjustment, one form of which is also illustrated in connection with Figs. 1, 2, and 3, and the details of which are further illustrated in Figs. 6, 7, 8, 9, 10, 11 and 12. This extension consists, briefly, of means for fixing pivot 37 on bearing member 21 at different points, the motion of part 22 due to slot 36 remaining the same in all cases.

When my device is provided with my improved extension adjustment, part 21 is formed with a central longitudinal slot 46, and pivot 37 is riveted or otherwise fixed to a cup shaped member 47 having outwardly directed flanges 48, 49, 50, 51, the height of which is equal to the height of slot 46, and which is therefore slidably therein. The depth of cup shaped member 47 is such that when the different parts are assembled together, a free space is left between flanges 48, 49, 50, 51, and the rear surface of member 21, sufficient for the passage of the locking member 52 represented in detail in Figs. 10, 11 and 12. Said locking member 52 is provided with lugs 53 projecting from its face and adapted to enter slots 54 provided at various points in member 21. Said locking member 52 is notched so as to conform to the outline of member 47; the same can be placed against the rear surface of part 21, lugs 53 entering the respective slots 54, in such a manner that the inward projections 55 of said locking member will pass through free spaces 56, 57, respectively between flanges 48, 49, and flanges 50, 51. Slots 54 are much longer than lugs 53 and allow the up and down motion of locking member 52; therefore when locking member 52 has been placed against the rear surface of part 21, the same is pushed downwardly so that lugs 55 will interlock with flanges 49, 51, and lugs 58 will interlock with flanges 48, 50. In this manner locking member 52 will be retained against the rear surface of part 21 by said flanges, while on the other hand, lugs 53 being inserted through slots 54, said locking member 52 will prevent any longitudinal motion of member 47 and will consequently fix in position pivot 37. By properly selecting the slots into which lugs 53 are inserted, pivot 37 can be fixed at the desired point to conform with the sides of the window for which the device is intended.

To effectively lock member 47 by means of member 52, I prefer to make the size of part 47 taper, and accordingly to make taper the sides of the notch registering therewith provided in locking member 52. This will wedge itself in position and maintain the devices assembled in a more effective way. This type of adjustable locking mechanism is particularly advantageous for the present purposes.

Figs. 13 and 14 represent a simplified form of my device in which 59 is an adjusting member, 60 an adjustable member, 61 is a cam-acting member provided with a slot 62 and an operating handle 63, and 64 is a pivot for the same mounted on member 59. The range of adjustment of this lock is limited to the amount obtainable by means of the slot, but in manufacturing the same, pivot 64 can be mounted or riveted on member 59 at suitably different points, so that by using the same parts locks adapted for use in different size windows can be made simply by assembling them in different relative positions. In Fig. 13, 65 represents a hole which can be produced in part 59 in order to rivet pivot 64 in the same, instead of being riveted in the position shown, in order to produce a smaller size lock. A lock thus assembled is only suitable for the size of window for which the same has been designed, but its lower cost of manufacture makes the same well adapted for general use.

In Figs. 19 and 20, I illustrate a lock quite similar in construction to that shown in Figs. 13 and 14, but the bearing member of which 66, has no clamping flange, and in which adjustable member 67 only is fitted with a serrated flange 68 exerting a clamping action against the outer sash of the window to which the device is applied. Bearing member 66 is fixed to the inner sash by means of a screw or screws 69, inserted through the lug or projection 70. When this style of lock is properly proportioned and sufficiently strong, its action is quite effective both in insuring the safety of a window and in preventing the rattling of the same, because while flange 68 pushes the outer sash against the outer frame molding, the inner sash will be pushed by the retaining screw or screws against the inner frame molding; the locking of the window will in other words be effected by forcing the two sashes apart. It may be noted however, that if proper care is exerted in placing the device fitted with a lock with an elongated slot, such as illustrated in Figs. 3 and 16, the same can also effectively prevent the rattling of the inner sash without the necessity of any additional locking nut, such as shown in Fig. 5. In fact, it will be sufficient to first extend the device in its clamping position and then to drive the re-

taining screw through the slot as near as possible to the end of said slot which remains toward the outer sash; the end of said slot therefore by acting against the retaining screw will hold the inner sash against the inner frame molding and will prevent the same from moving unless the clamping action of the device is released.

In designing my device I have carefully avoided the use of threaded parts which are usually more costly to manufacture than die produced sheet metal parts; and I also have avoided as much as possible the use of parts projecting from the surface of the device which would render the same less attractive in design and appearance.

The slotted member controlling the sliding relative motion of the two parts of which my device is composed, can be made with a detached handle or with a handle integral therewith as desired; and the slot provided in the same may be caused to follow any suitable curve which will fulfil the requirements of the device.

It is to be understood that my device can be modified in its various details without substantially departing from the spirit of my invention and I reserve myself the right of bringing to the same all those changes and modifications which may be rendered necessary or useful, to meet special requirements of individual cases, and which fairly enter into the scope of the appended claims.

Having thus described and ascertained the nature of my invention what I claim as new and desire to secure by Letters Patent of the United States is:

1. In a sash lock, the combination of two plates slidably connected to each other having serrated flanges, means for operating the same, and a lug projecting from one of the said plates for movably attaching the device to the inner sash of a window; for the purposes as set forth.

2. In a sash lock, the combination of two plates slidably connected to each other having serrated flanges, means for operating the same, and an attaching lug integral with one of the said plates having an elongated slot; for the purposes as set forth.

3. In a sash lock, the combination of a bearing plate, an adjustable plate slidably connected thereto, a cam-acting member pivotally connected to said bearing plate operating said adjustable plate, and means depending from one of the said plates for adjustably securing the same to the inner sash of the window to which the device is applied.

4. In a sash lock the combination of a bearing plate, an adjustable plate slidably connected thereto, flanges integral with said plates provided with oppositely engaging serrations, a cam-acting member pivotally

connected to said bearing plate operating said adjustable plate, and means depending from one of the said plates for securing the same to the inner sash of the window to which the device is applied.

5. In a sash lock, the combination of a bearing plate, an adjustable plate mounted upon and slidably connected thereto, flanges integral with said plates provided with oppositely engaging serrations, a slotted cam-acting member pivotally connected to said bearing plate, a member projecting from the surface of said adjustable plate through said slotted cam-acting member and controlled thereby for operating said plate, and an attaching lug integral with one of the said plates, having an elongated slot; for the purposes as set forth.

6. In a sash lock, in combination with a bearing member, an adjustable member slidably connected thereto, and means for operating the same, means for securing said operating means on said bearing member at different points comprising an element having outwardly directed flanges projecting through said bearing member, and a locking element inserted between said flanges and said bearing member, interlocking with said member; for the purposes as set forth.

7. In a sash lock, the combination of a bearing plate provided with a longitudinal slot and with a plurality of transverse positioning slots, an adjustable plate slidably connected thereto, serrated flanges integral with said plates, an element having outwardly directed flanges projecting through said longitudinal slot, a cam-acting member pivotally connected to said element operating said adjustable plate, and a locking element inserted between said flanges and said bearing plate, having lugs projecting through said positioning slots; for the purposes as set forth.

8. In a sash lock, the combination of a bearing plate, provided with a longitudinal slot and with a plurality of transverse positioning slots, an adjustable plate slidably connected thereto, serrated flanges integral with said plates, operating means for said plates, an element carrying said operating means projecting through said longitudinal slot having outwardly directed flanges and tapering sides, and a locking element inserted between said flanges and said bearing plate, having lugs projecting through said positioning slots, and provided with a slot having correspondingly tapering sides.

9. In a sash lock, the combination of a bearing plate provided with a longitudinal slot and with a plurality of transverse positioning slots, an adjustable plate slidably connected thereto, flanges integral with said plates having oppositely engaging serrations, an element projecting through said

longitudinal slot having outwardly directed flanges, a slotted cam-acting member pivotally mounted on the same, a member projecting from the surface of said adjustable plate through said slotted cam-acting member and controlled thereby, a lug integral with one of the said plates having an elongated slot, and a locking member inserted

between said flanges and said bearing plate, having lugs projecting through said positioning slots; substantially as described, and for the purposes as set forth. 10
